FOUNTAIN INKWELL

Eddie P. Truesdale, Camden, S. C.

Application March 16, 1936, Serial No. 69,212

8 Claims. (Cl. 120—59)

This invention relates to an ink well of the fountain type and one object of the invention is to provide the ink well with an improved type of ink receiving well or pocket into which ink flows from a reservoir formed by the body of the ink well, the ink receiving pocket being provided with an entrance so constructed that while the pen may be freely inserted and removed therefrom, the pen holder will be limited in its inward movement and prevented from being covered with ink by being inserted too far into the entrance of the ink receiving pocket.

Another object of the invention is to so construct the entrance to the ink receiving pocket that it will be located above the same when the ink well is in an upright position and also above the ink receiving chamber or reservoir when the ink well is bent upon its back in position for filling and thus permits the inkwell to be easily filled through the entrance neck of the pocket.

Another object of the invention is the provision of an improved closure for the entrance neck, the closure being pivotally mounted so that it will normally remain in position to close the entrance neck but permit it to be swung inwardly by pressure applied to its lower end portion when a pen is thrust into the entrance.

Another object of the invention is to so construct and mount the closure that when the ink well is in an upright position outward movement of the lower end of the closure will be limited, whereas when the ink well is turned to an inverted position, this end portion of the closure may be easily swung outwardly to such an extent that the closure will slide through slots in which it is pivotally mounted and out of the entrance neck, thus leaving the entrance neck unobstructed and permitting a fresh supply of ink to be freely poured through the neck and into the reservoir chamber.

Another object of the invention is to provide an ink well of the fountain type wherein an air passage is provided vertically in the reservoir chamber over the inner end portion of the ink receiving well or pocket and thus permit air to pass upwardly into the upper portion of the reservoir when the level of ink in the pocket has been reduced by use or evaporation to such a point that a replenishing of the ink in the pocket is necessary.

The invention is illustrated in the accompanying drawing, wherein

Figure 1 is a sectional view taken vertically through the improved ink well.

Figure 2 is a view showing the improved ink well in front elevation.

Figure 3 is a sectional view taken vertically through the ink well along the line 3—3 of Figure 1.

Figure 4 is a horizontal sectional view taken along the line 4—4 of Figure 1.

Figure 5 is a fragmentary view showing the ink well in an inverted position to permit removal of the closure.

Figure 6 is a perspective view of the closure.

This improved ink well may be formed of metal, glass or any other desired material and has a body 1 which is preferably rectangular when viewed in vertical or horizontal cross section but may be of any desired shape and also of any dimensions according to the quantity of ink which it is desired to have the ink receiving chamber or reservoir 2 hold. The bottom 3 of the reservoir chamber 2 is spaced upwardly above the lower end of the body 1, thus providing space in the lower portion of the body to receive the well or pocket 4 into which a quantity of ink flows from the reservoir chamber. By referring to Figure 1 it will be seen that the pocket 4 extends through the front wall of the body under the neck 5 which has been shown enclosed in a threaded jacket 6 and serves as an entrance for the ink receiving pocket. It will be understood that if so desired the neck 5 and its jacket 6 may be formed as an integral structure instead of forming the jacket separate from the neck and then securing it about the neck. By having the neck threaded, a cap 7 may be screwed tightly thereon to prevent evaporation when the ink well is not in use. The mouth 8 of the jacket which projects outwardly beyond the neck 5 is flared, as clearly shown in Figures 1 and 4, so that ink may be guided into the neck when filling the ink well. This also provides a bordering surface about the outer end of the neck constituting a good abutment to engage the end of a pen holder and limiting movement of the pen holder and a pen inwardly through the neck, as indicated by dotted lines in Figure 1. A channeled strip 9 extends vertically in the reservoir chamber 2 against the front wall of the body over the inner end portion of the pocket 4 and serves as an air passage through which air may travel upwardly from the neck and pocket into the upper end of the reservoir chamber so that ink may flow from the reservoir chamber into the pocket to replenish the supply therein when necessary without bubbling which would be liable to cause ink to have surging motion in the pocket and

50
55

spill outwardly through the neck. It should also be noted that this channeled strip or air conduit 9 serves to block the upper end of a major portion of the pocket within the body and thus prevent excessive flow of ink from the reservoir into the pocket.

In order to normally close the neck and prevent entrance of dust into the pocket and also prevent excessive evaporation of ink in the 10 pocket when the cap 7 is removed, there has been provided a closure 10 having the form of a semi-circular block of metal which is of such width that it fits snugly into the neck between the flat side walls thereof. A face plate 11 is 15 fixed to the flat front or outer face of the closure block and is of such length that one end portion of the plate projects from the block to provide a lip 12 adapted to engage the upper end portion of the sloping front wall 13 of the pocket 20 4 and limit outward movement of the lower end of the closure when the ink well is in the upright position shown in Figure 1. By referring to this figure it will be readily seen that while the lower end portion of the closure block may 25 be easily swung inwardly by pressure of a pen point applied thereto, it cannot move outwardly beyond the position shown in full lines in this figure. Therefore, the ink in the pocket will be shielded to prevent dust accumulating in the ink 30 30 in the pocket. Pivot pins 14 extend from opposite side edges of the face plate 11 midway ends of the front face of the closure block and these pivot pins are engaged in seats 15 which are in the form of grooves formed in opposite side 35 walls of the neck with their outer end portions extending across the mouth of the jacket 6. These grooves extend inwardly at a downward incline with their inner ends terminating opposite each other midway the depth of the neck 40 and as the inner ends of the grooves are rounded, as shown clearly in Figure 5, the pivot pins can turn freely in the grooves and thus permit the closure block to be easily moved inwardly when a pen is inserted into the pocket 4 and then return to the closed position as the pen is withdrawn. Attention is called to the fact that ends 45 of the block are out of contact with the upper wall of the neck and the sloping front wall of the pocket but that the lip 12 projects from the 50 closure block to such an extent that when the ink well is in the upright position this tongue or lip may engage the sloping front wall of the pocket and limit outward movement of the lower portion of the closure beyond the position shown 55 in full lines in Figure 1. When, however, it is desired to remove the closure block and thus permit the reservoir chamber to be refilled with ink, the ink well may be disposed in an inverted position, as shown in Figure 5, and the pivot 60 pins may then slide along the grooves 15 to such a position that the arcuate face of the closure block will rest upon the wall of the neck and the distance between the pivot pins and the sloping wall 13 of the ink receiving pocket will be greater 65 than the distance between the pivot pins and the outer end of the lip or tongue 12. Therefore, when pressure is applied to the outwardly projecting portion of the closure block by a pen, pencil, or other implement indicated by dotted 70 lines in Figure 5, the closure block may be completely rotated in the neck and as the lip 12 moves outwardly beyond the outer end of the sloping wall 13 of the neck, the pivot pins will slide downwardly through the grooves 15 and the 75 closure block passed outwardly from the neck.

The ink well may then be set upon its rear wall with its jacketed neck extending upwardly and a fresh supply of ink poured through the neck to fill the reservoir chamber, after which the closure block may be replaced and the ink well set in an upright position in which ink will flow from the reservoir into the pocket until the level of the ink in the pocket reaches such a height that the lower end of the air passage or conduit 5 will be closed and a liquid seal formed which 10 will prevent additional flow of ink from the reservoir into the pocket. As the ink in the pocket is gradually reduced by use and slow evaporation, the level of the ink will finally reach a point in spaced relation to the lower end of the air 15 passage and air may then pass upwardly through this passage into the upper end of the reservoir and a fresh supply of ink will flow from the reservoir into the pocket until the lower end of the air passage is again closed. By replacing the cap 7 when the ink well is not in use excessive 20 evaporation of ink in the pocket will be prevented and also dust prevented from accumulating upon the outer face of the closure and the outer end portion of the neck. 25

Having thus described the invention, what is claimed as new is:

1. In a fountain ink well, a hollow body defining a reservoir, the bottom of the body being spaced upwardly from the lower end thereof, an auxiliary receptacle extending through a wall of the body under the bottom and providing a pocket having its inner portion communicating with said reservoir, a tube extending vertically in said reservoir above the inner portion of said pocket to provide an air passage extending upwardly from the pocket to adjacent the upper end of the reservoir, a neck for the outer portion of said pocket open at its front and having side walls formed with grooves extending inwardly at a downward incline, and a closure block for said neck pivotally mounted in the neck above the outer portion of the pocket by guide pins engaged in said grooves, said closure block being semi-circular in shape and having a lip projecting from one end to engage the upper forward portion of the pocket and limit outward movement of the lower portion of the closure block, the other end of the closure block being spaced from the upper portion of the neck when the ink well is in an upright position, whereby upon inverting the ink well the pivot pins may slide towards outer ends of the grooves to move the lip out of engagement with the wall of the pocket and permit tilting of the block forwardly out of the neck. 50 55 60 65 70 75 80 85 90 95 100

2. In a fountain ink well, a body defining a reservoir chamber, an auxiliary receptacle having an inner portion communicating with the lower end of the reservoir chamber and an outer portion projecting forwardly from the body and open at its top, an air conduit extending vertically in the reservoir and having an open upper end spaced from the top of the body and an open lower end communicating with the inner portion of the auxiliary receptacle, a neck above the auxiliary receptacle open at its front and communicating with the open upper end of the outer portion of the auxiliary receptacle, tracks at opposite sides of said neck extending inwardly at a downward incline, and a closure fitting snugly in the neck and having pins projecting from its opposite sides and engaged in said tracks to pivotally mount the closure and slidably mount the closure for movement into and out of 75 60 65 70 75

the neck, said closure having a lip at its lower end for engaging a wall of the auxiliary receptacle when the body is in an upright position and limit swinging movement of the lower portion 5 of the closure toward the outer end of the neck.

3. In a fountain ink well, a hollow body defining an ink reservoir, an auxiliary receptacle disposed partially under the reservoir to provide an inner portion communicating with the reservoir 10 and an outer portion open at its upper end, an entrance neck for the outer portion of the auxiliary receptacle extending upwardly therefrom and open at its front, a jacket about said neck projecting forwardly therefrom and having a 15 flaring mouth constituting an abutment to engage an end of a pen holder when a pen is thrust through the neck into the auxiliary receptacle and limit inward movement of the pen holder and pen, and a closure pivotally and 20 removably mounted in the neck and formed with a lip at one end to engage a wall of the auxiliary receptacle and limit tilting movement of the closure and prevent removal of the closure from the neck when the ink well is in an upright position. 25

4. In a fountain ink well, a reservoir having an outlet at its bottom, an auxiliary receptacle defining an ink receiving pocket communicating with the reservoir through the opening in the bottom thereof and having a portion projecting from the reservoir and open at its top, an entrance neck rising from the open top of the projected portion of the pocket and open at its front, and a closure for said neck having pivots 30 at its sides engaged in seats extending inwardly at a downward incline from the open end of the neck and open at their upper ends. 35

5. In a fountain ink well, a reservoir having an outlet at its bottom, an auxiliary receptacle 40 defining an ink receiving pocket having a portion communicating with the reservoir through the opening in the bottom thereof and a portion projecting forwardly from the reservoir and open at its top, a neck for the ink pocket rising from 45 the forwardly projecting portion thereof about its open upper end and open at its front, and a closure inserted into the neck through the open front end thereof and pivotally mounted and held against removal when the ink well is in an up- 50 right position, said closure having means associated therewith to limit tilting movement of the

closure in one direction when the ink well is in the upright position.

6. In a fountain ink well, a reservoir having an outlet at its bottom, an ink receiving pocket communicating with the reservoir through the opening in the bottom thereof and having a portion projecting forwardly from the reservoir and open at its top, a substantially horizontal neck 5 communicating with the open upper end of the forwardly projecting portion of said pocket and 10 open at its front, a closure pivotally mounted within said neck above said pocket in a substantially upright position, means to limit pivotal movement of the closure in one direction in the neck when the ink well is in an upright position, 15 and a closure detachably carried by the neck for closing the outer end of the neck.

7. In a fountain ink well, a reservoir having an outlet at its bottom, an ink receiving pocket communicating with the reservoir through the outlet openings thereof and having a portion projecting from the reservoir and open at its top, a neck rising from the projecting portion of the pocket and open at its front and at opposite sides provided with tracks extending inwardly from 20 the open front of the neck at a downward incline, and a closure block fitting into the neck through the open front thereof and having pivot pins engaged in the track to slidably and pivotally mount the closure, and a tongue extending 25 from one end of the closure block to limit tilting movement of the closure block and prevent removal of the closure block from the neck when the ink well is in an upright position. 30

8. In a fountain ink well, a reservoir having an outlet at its bottom, an ink receiving pocket communicating with the reservoir through the opening in the bottom thereof and having a portion projecting from the reservoir and open at its top, a neck rising from the projected portion 40 of the pocket and open at its front, a jacket for said neck, opposite side walls of the neck being formed with seats extending inwardly at a downward incline and open at their outer ends, a closure in said neck having pivot pins at its sides 45 engaged in said seats to pivotally mount the closure, and a cap detachably engaged with the jacket to close the outer end of the neck when in place. 50
